UNITED STATES PATENT OFFICE.

CEPHAS B. ROGERS, OF DANBURY, CONNECTICUT.

DESIGN FOR AN ELECTRIC-LIGHT BRACKET.

58,688.

Specification for Design.

Patented Aug. 9, 1921.

Application filed December 3, 1920. Serial No. 428,132. Term of patent 3½ years.

To all whom it may concern:

Be it known that I, CEPHAS B. ROGERS, a citizen of the United States, residing at Danbury, county of Fairfield, and State of Connecticut, have invented a new, original, and ornamental Design for Electric-Light Brackets, of which the following is a specification, reference being had to the accompanying drawing, forming part thereof.

Figure 1, is a front elevation; and

Fig. 2, is a bottom end elevation of an electric light bracket, showing my new design.

I claim:

The ornamental design for an electric light bracket, as shown.

CEPHAS B. ROGERS.
